HEEL PROTECTOR

William H. Klein, 810 East End Ave., Pittsburgh, Pa.

Filed Oct. 11, 1961, Ser. No. 67,048

Term of patent 7 years

(Cl. D7—5)

Fig. 1

Fig. 2

Fig. 3

Fig. 4

FIGURE 1 is a side elevational view of a heel protector showing my new design. The partial broken line showing of a shoe is for illustrative purposes only;

I claim:

The ornamental design for a heel protector, as shown and described.
